UNITED STATES PATENT OFFICE.

THOMAS HOLLIDAY, OF HUDDERSFIELD, COUNTY OF YORK, ENGLAND.

PRODUCTION OF AZO COLORS ON COTTON FABRICS.

SPECIFICATION forming part of Letters Patent No. 271,636, dated February 6, 1883.

Application filed August 22, 1882. (No specimens.)

To all whom it may concern:

Be it known that I, THOMAS HOLLIDAY, of Huddersfield, county of York, England, have invented a new and useful Improvement in 5 Coloring-Matters, of which the following is a full, true, and exact description.

In the production of azo coloring-matters on cotton or other textile fibers made by combining diazo compounds with the naphthols in 10 the presence of the fiber, the diazo compound employed has been used just as it is produced by the action of nitrous acid on amidated compounds and the color developed by means of an alkali.

15 This invention consists in the further treatment of the diazo bath by neutralizing the acid in the solution before employing the same for dyeing or printing, and for this purpose I prefer to use the carbonates of the metals of the 20 alkaline earths.

As an example of the manner in which the invention can be carried into effect, I employ a diazo bath made in the usual manner—say by treating an amido compound with muriatic acid 25 and nitrite of soda—and after the reaction is complete I add to it, say, carbonate of lime till the acid is neutralized, which can be ascer-

tained in the usual manner. The solution can then be filtered and employed for the purpose of producing azo colors on the fiber, and if the 30 fiber has been previously oiled and passed through a warm solution of naphthol in the manner described in my patent No. 252,317, the color will be at once developed without further treatment with alkali. 35

Having thus fully described my invention and the manner of carrying the same into effect, what I claim as my invention, and desire to secure by Letters Patent, is—

The direct production of azo colors upon cotton or other textile fabrics by the action of a neutralized bath of the diazo compounds upon fiber previously treated with the naphthols or phenols, thereby immediately producing the color in the bath without subsequent treatment, substantially as described. 40 45

In witness that I claim the foregoing I have hereunto set my hand.

THOMAS HOLLIDAY.
